JAY B. RHODES, OF KALAMAZOO, MICHIGAN, ASSIGNOR TO WESTERN WHEELED SCRAPER COMPANY, OF AURORA, ILLINOIS, A CORPORATION OF ILLINOIS.

DUMP-CAR.

1,294,832

Specification of Letters Patent. Patented Feb. 18, 1919.

Application filed July 6, 1917. Serial No. 178,905.

To all whom it may concern:

Be it known that I, JAY B. RHODES, a citizen of the United States, and a resident of Kalamazoo, in the county of Kalamazoo and State of Michigan, have invented certain new and useful Improvements in Dump-Cars, of which the following is a specification, reference being had to the accompanying drawings:

10 My invention relates to dump cars of the general type shown and described in my pending application, Serial No. 98,495, filed May 19, 1916, in which the lateral tilting of the car bed to discharge its load as well as 15 to restore it to its normal position is effected by power operated pistons or plungers acting through folding thrust bars, the members of the thrust bars being connected by knuckle joints so that they may swing out of line 20 with each other in one direction, but not in the other. In the construction shown and described in my said application the car bed is normally held against tilting by means of certain locking devices comprising chains 25 or other flexible connections connected to the sides of the car bed, and also connected with the under body of the car by latch mechanism which is automatically released by the actuation of the appropriate bed-tilting devices.

30 The car which forms the subject-matter of the present application employs bed-tilting or rocking devices very similar to those of my said application, but instead of employing chain locking devices for holding the car bed 35 in its normal or horizontal position when in use I employ folding struts interposed between the side portions of the car bed and the under body of the car and arranged to coöperate with the bed rocking mechanism.

40 so as to permit the bed to be dumped or restored to its normal position as necessary. I am aware that it is not broadly new to employ struts for supporting the side portions of a dump car bed, but I believe myself to be 45 the first to employ for that purpose jointed or folding struts which are constructed and arranged so that they fold or collapse when the appropriate bed rocking mechanism is operated and so permit the car to be dumped, 50 and when the bed is righted automatically restored to operative position, and which also remain in operative position when the car is dumped at the opposite side so

that they prevent the bed from being thrown over beyond its normal position when it is 55 being righted.

In the accompanying drawings which illustrate one form in which my invention may be employed:

Figure 1 is a side view of the greater part 60 of a dump car;

Fig. 2 is an end view thereof;

Fig. 3 is an enlarged detail, being a vertical cross-section on line 3-3 of Fig. 5;

Fig. 4 is a vertical cross-section of the car 65 substantially on line 4-4 of Fig. 1;

Fig. 5 is an enlarged detail illustrating the arrangement of one of the springs which aid in restoring the struts to their normal or operative position;

Fig. 6 is a vertical cross-section on line 70 6-6 of Fig. 1, the side gates of the car bed being omitted;

Fig. 7 is an enlarged detail showing one of the thrust bars and one of the struts and 75 certain parts connected therewith; and

Figs. 8 and 9 are similar views showing changed positions of the parts.

Referring to the drawings,—10 indicates the car bed which is provided with side gates 80 11 of any approved construction. 12 indicates longitudinally-extending I-beams which

form the basis of the under body of the car and are mounted upon trucks 13. 14 indicates transversely-disposed bolsters placed 85 at intervals and connected to the I-beam 12.

Said bolsters carry bumpers 15 which limit the extent to which the car bed may tilt. 16 indicates standards arranged at intervals along the under body on the center line 90

thereof and supporting pivots 17 on which the car bed is supported by means of depending lugs 18 secured centrally to the under side of the bed as shown in Fig. 4. The arrangement is such that the car bed may 95

be tilted to discharge its load at either side of the under body as is common in dump cars of this type. 19-20 indicate folding thrust bars at opposite sides of the car at or near the longitudinal center thereof, said 100

thrust bars being pivoted at their upper ends to the under side of the car bed as shown at 21-22 in Fig. 6 so that they may swing laterally in folding. Each of said thrust bars comprises two members *a*-*b* connected 105

by an offset pivot *c* so as to form a knuckle

joint which may break inwardly as shown in Fig. 6. Each of the members *b* is provided at its lower end with a curved finger *d* and with a recess *e* as shown in said figure. 5 23—24 indicate links which at their inner ends are mounted upon one of the pivot pins 17 and at their outer ends are pivotally connected to the lower ends of the members *b* by pivots 25—26, respectively. When the 10 members *a*—*b* of the thrust bars 19—20 are alined the links 23—24 serve to hold them so that they assume a downwardly and inwardly inclined position, and when the joint of either thrust bar is broken when folding 15 it the link connected with said thrust bar holds the lower end of the member *b* thereof out while its knuckle swings inwardly, thus causing the thrust bar to fold properly.

The thrust bars 19—20 are adapted to 20 coöperate with plunger rods 27—28 carried in plungers 29—30, respectively, working in cylinders 31—32 which are mounted on the under body of the car at opposite sides thereof and are arranged to be supplied with 25 compressed air from any suitable source, such as a locomotive or a compressed air cylinder. The usual valve mechanism is provided so that the compressed air may be admitted to or exhausted from either cylinder at pleasure. When the compressed air 30 is admitted to either cylinder, as for example the cylinder 31, its plunger will be raised so as to carry its plunger rod 27 upward into engagement with the lower end of the 35 thrust bar 19. To insure proper engagement of these parts, the upper end of the plunger rod 27 is provided with a guide link 33 pivoted to it and to the pin 17, and the plunger rod is arranged to rock laterally under the 40 action of said guide link. Said plunger rod is also provided with a rounded head 34 adapted to fit in the recess *e* at the lower end of the thrust bar 19. Thus when the plunger rod 27 is projected by the admission of compressed air to the cylinder 31 the head 34 45 will enter the recess *e* and apply power to the thrust bar 19 along a line which falls inside of its pivot *c*, and consequently has no tendency to break the joint. That side 50 of the car bed will, therefore, be lifted so as to rock it about its pivots 17 and dump the load at the opposite side of the car. In like manner, the plunger rod 28 is provided 55 with a guide link 35 which has a head 36 corresponding to the parts 33 and 34 already described. When the car bed is tilted so as to discharge at the right, as above described, it will be evident that the thrust bar 20 will move down with the bed, the lower end of 60 said thrust bar being guided by the link 24. At this time the plunger rod 28 occupies the position shown in Fig. 6, being then at the left hand side of its plunger 30. As the car bed descends the finger of the thrust bar 20 will strike a laterally projecting lip 37

at the upper end of the plunger rod 28 and the thrust thereby applied to the thrust bar being outside the line of the pivots *c* and 22 will cause said thrust bar to buckle and fold, thereby permitting that side of the bed to 70 descend. In like manner, the plunger rod 27 is provided with a lip 38 which performs a similar function when the load is dumped at the opposite side of the car. From the foregoing description it will be apparent 75 that when the bed is tilted in either direction from its horizontal position the thrust bar at the high side of the bed is not folded and its members remain in operative relation to each other, but the thrust bar at the low 80 side of the bed is folded inwardly under the bed. In restoring the bed to its normal position, air is admitted to the cylinder at the low side causing the plunger rod at that side to rise into engagement with the folded 85 thrust bar, thereby rocking the bed in the opposite direction until it resumes its horizontal position. The retraction of the plunger rod permits the members of the folded thrust bar to resume their operation relation 90 to each other by gravity, but in order to insure this action I prefer to provide each of the thrust bars 19—20 with a spring 39 mounted upon the pivots 21—22 of the thrust bars, as best shown in Fig. 5. The springs 95 39 are arranged to act on the members *a* of the thrust bars so as to swing them outwardly and bring the members *a*—*b* into complete alinement.

With the exception of the springs 39 just 100 referred to, the construction thus far described is shown and described in my said application, and is, therefore, not claimed herein separately but only in combination with the features which remain to be described.

The car bed is normally held in its horizontal position by folding struts interposed between the side portions of the bed and the under body. In the construction shown I 110 employ two pairs of these struts, one pair near each end of the car. 40 indicates one of the struts at one side of the car and 41 one of the struts at the opposite side, as shown in Fig. 4. Each of these struts comprises two members *f*—*g* connected together by an offset pivot *h* to form a knuckle joint which may break inwardly. 42—43 indicate 115 pivots connecting the upper members *f* of the struts 40—41 with the under side of the car bed. Springs similar to the springs 39 are mounted on the pivots 42—43 for restoring the members of each strut to an alined position. At the lower end of each 120 of the members *g* is a shoe *i*, and these shoes bear upon rollers 44—45 mounted on the bolsters 14 near the bumpers 15, as shown in Fig. 4. The rollers 44—45 are so placed 125 that when the members of the struts 40—41 are in alinement lines connecting the pivots 130

42—43 with the axes of the rollers 44—45, respectively, lie inside of the pivots *h*, and consequently the struts are held against breaking. It will be noted that the shoes *i* 5 extend outward beyond the lines of the pivots 42^h and 43^h, respectively, the object of which arrangement is to cause the struts to break and fold when their lower ends are swung inwardly far enough to carry the line 10 of thrust outside the pivots *h*. 46—47 indicate rock shafts suitably journaled in the standards 16 or other suitable supports, and extending longitudinally of the car. Preferably four of these rock shafts are used, 15 two at each end. 48—49 indicate crank arms carried by the rock shafts 46—47, respectively, adjacent to the end portions of the car, as shown in Fig. 4. 50—51 indicate links connecting the cranks 48—49 with the 20 members *g* of the struts 40—41 respectively. It will be apparent that by rocking the shafts 46—47 the members *g* may be swung laterally, the shoes *i* riding on the rollers 44—45, and that the links 50—51 also serve to hold 25 the lower ends of the struts 40—41 in position. Preferably the arm 49 and link 51 are in offset relation to the arm 48 and link 50, as indicated in Fig. 4, to permit a wider range of movement of the parts. 52 indicates springs mounted on the rock shafts 46—47, as indicated in Fig. 1, which act 30 normally to hold the arms 48—49 and links 50—51 in the position shown in Fig. 4, thereby holding the struts 40—41 in operative position. 53 indicates a crank secured to the rock shaft 46 and extending over the rock shaft 47 adjacent to the link 35 in position to be engaged by a swinging hook 54 pivoted 35 intermediately upon said link, as shown at 40 55 in Fig. 6. 56 indicates a similar crank which is connected to the rock shaft 47 and extends over the rock shaft 46 adjacent to the link 33 in position to be engaged by a hook 57 pivotally mounted at 58 upon said link. It will be apparent that when the 45 plunger rod 28 is projected to dump the car at the left hand side the link 35 will swing upwardly, carrying with it the hook 54 which will act to swing the crank 53 upward, thereby rocking the rock shaft 46 in a counterclockwise direction. This will move the link 50 to the right thereby swinging the lower end of the strut 40 in the same direction. As illustrated in Fig. 8, the line of 50 thrust is thus brought between the toe of the shoe *i* and the pivot 42 so that it is outside of the pivot *h* and consequently the strut 40 is caused to buckle and fold inwardly as the left hand side of the car bed descends, 55 as illustrated in Fig. 9, thus permitting the car to be dumped. As the plunger 28 continues to move upward in the dumping operation, the member *g* of the strut 40 is carried over to the right as indicated in dotted lines in Fig. 9, but when said plunger rod

is retracted after dumping, said member *g* is moved back to the left by the rocking of the shaft 46 effected by the spring 52. During this operation the strut 41 at the opposite side of the car is not affected as the 70 plunger rod 27 remains retracted. In restoring the bed to its normal position after it has been dumped in the manner described, air is admitted to the left hand cylinder 31 thereby causing its plunger rod 27 to rise 75 and lift the left hand side of the bed, as has been described. During this operation it is of course necessary that the strut 41 at the right hand side of the car remain in its operative position, and consequently to prevent the projection of the plunger rod 27 from moving said strut out of operative position at this time, provision is made for releasing the hook 57 from engagement with the crank 56 by which the rock shaft 47 80 is rocked. This release is effected by means of a lug 59 which depends from the car bed in position to engage the upper end 57^a of the hook 57 and move the hook out of engagement with the crank 56 when the car 85 occupies the inclined position which it assumes when dumped to the left, as illustrated in Fig. 9. Thus the projection of the plunger 27 in restoring the bed to its normal position is effected without rocking 90 the shaft 47, and consequently without moving the strut 41 out of operative position. When the car bed is in its normal position the lug 59 does not act upon the hook 57 when the plunger rod 27 is projected as the 95 upper end 57^a of said hook then passes under the lower end of said lug without operatively engaging it, and consequently the hook 57 remains in operative engagement with the crank 56 and rocks the shaft 47 for the purpose described. A similar lug 60 is provided to coöperate with the upper end 54^a of the hook 54. Both the hooks 54 and 57 are arranged to normally engage their respective cranks under the action of gravity. 100 As soon as the car bed is righted after having been dumped at either side, the members of the strut at the dumping side will swing into alignment under the action of gravity assisted by the spring 52 and the spring mounted 105 on the upper pivot, as 42, of the strut, and such strut will resume its position between the roller 44 or 45, as the case may be, and the upper pivot of the strut, as illustrated in Figs. 4 and 7, thus locking the 110 bed in its normal position.

While I have described with considerable particularity the embodiment of my invention illustrated in the drawings, I wish it to be understood that my invention is not 125 limited to the specific construction shown and described except in so far as such construction is specifically claimed, but includes generically the subject-matter of the broader claims.

What I claim as my invention and desire to secure by Letters Patent, is—

1. A dump car comprising an under body, a bed mounted thereon and adapted to tilt to discharge its load, a strut composed of a plurality of foldable members, the upper end portion of said strut being pivotally connected with the bed, and the lower end portion thereof being adapted to bear on the under body, for normally preventing tilting of the bed in one direction, and means connected with the lower end portion of said strut for moving the same laterally out of operative engagement with the under body.

15 2. A dump car comprising an under body, a bed mounted thereon and adapted to tilt to discharge its load, a strut composed of upper and lower members pivotally connected together, the upper member being pivotally connected with the bed, and the lower member having an end bearing on the under body, for normally preventing tilting of the bed in one direction when said members are in operative position, and means for moving the lower end of said lower member laterally out of operative engagement with the under body.

3. A dump car comprising an under body, a bed mounted thereon and adapted to tilt to discharge its load, a strut composed of upper and lower members connected together by a knuckle joint, said strut being pivotally supported at one end to swing laterally between one side of the bed and the under body, the other end of said strut having a thrust bearing on the under body for normally preventing tilting of the bed in one direction when said members are in operative position, and means for moving the latter end of said strut laterally out of operative position.

4. A dump car comprising an under body, a bed mounted thereon and adapted to tilt to discharge its load, a strut composed of a plurality of foldable members, the upper end portion of said strut being pivotally connected with the bed, and the lower end portion thereof being adapted to bear on the under body for normally preventing tilting of the bed in one direction, power operated means for tilting the bed to dump the same, and means coöperating therewith for causing said strut to fold to permit tilting of the bed.

55 5. A dump car comprising an under body, a bed mounted thereon and adapted to tilt to discharge its load, a strut composed of members connected together by a knuckle joint interposed between one side of the bed and the under body for normally preventing tilting of the bed in one direction, said strut being pivotally connected at its upper end with the car bed and being adapted at its lower end to bear on the under body and to swing laterally to carry the knuckle

joint across the line of thrust, power operated means for tilting the bed to dump the same, and means coöperating therewith for moving said strut laterally out of operative position, to permit the bed to tilt.

6. A dump car comprising an under body, a bed mounted thereon and adapted to tilt to discharge its load, a folding strut interposed between one side of the bed and the under body for normally preventing tilting of the bed in one direction, said strut being pivotally connected at its upper end with the car bed and being provided at its lower end with a laterally projecting shoe adapted to bear on the under body and to move laterally out of operative position, power operated means for tilting the bed to dump the same, and means coöperating therewith for moving said strut laterally out of operative position, to permit the bed to tilt.

7. A dump car comprising an under body, a bed mounted thereon and adapted to tilt to discharge its load, a strut pivotally connected with the bed and interposed between one side of the bed and the under body for normally preventing tilting of the bed in one direction, said strut being composed of upper and lower foldable members, the lower member having a thrust bearing on the under body and being movable out of contact therewith, power operated means at the opposite side of the bed for tilting the same, and means connected with said lower member and operated by said power operated means for automatically moving said strut laterally out of operative position, to permit the bed to tilt.

8. A dump car comprising an under body, a bed mounted thereon and adapted to tilt to discharge its load, a strut interposed between one side of the bed and the under body for normally preventing tilting of the bed in one direction, said strut being composed of members connected together by a knuckle joint and having a laterally projecting shoe at its lower end, the upper end of said strut being pivotally connected with the bed, and means for moving said strut laterally out of operative position to permit the bed to tilt.

9. A dump car comprising an under body, a bed mounted thereon and adapted to tilt to discharge its load at either side of the car, struts composed of a plurality of foldable members pivotally mounted to swing laterally between the side portions of the bed and the under body and having thrust bearings on the under body for normally preventing tilting of the bed when said struts are in operative position, power operated means at the opposite sides of the under body for tilting the bed to dump the same, and to restore it to its normal position, and means operated by the actuation of one of said power operated means for moving the lower end of the

130

strut at the opposite side of the car laterally out of operative position, to permit the bed to tilt in one direction.

10. A dump car comprising an under body, 5 a bed mounted thereon and adapted to tilt to discharge its load at either side of the car, struts composed of a plurality of foldable members interposed between the side portions of the bed and the under body for 10 normally preventing tilting of the bed, power operated means at the opposite sides of the under body for tilting the bed to dump the same, and to restore it to its normal position, means operated by the actuation 15 of one of said power operated means for moving the strut at the opposite side of the car out of operative position to permit the bed to tilt in one direction, and means operated by the tilting of the bed for automatically disconnecting the other power operated means from the strut at the opposite side of the car whereby the latter strut will remain in operative position while the car bed is being restored to its normal position.
- 20 11. A dump car comprising an under body, a bed mounted thereon and adapted to tilt to discharge its load, a folding thrust bar comprising jointed members, one of said members being pivotally connected with the 25 bed at one side of the axis thereof, power operated means adapted to engage the other member while said members are alined to move the same endwise for tilting the bed, means for guiding said thrust bar, a strut 30 interposed between the opposite side of the bed and the under body and pivotally connected at its upper end with the bed to swing laterally, and devices operated by said power operated means for moving said strut out of 35 operative position to permit the bed to tilt.
12. A dump car comprising an under body, 40 a bed mounted thereon and adapted to tilt to discharge its load, a folding thrust bar comprising jointed members, one of said members being pivotally connected with the 45 bed at one side of the axis thereof, power operated means adapted to engage the other member while said members are alined to move the same endwise for tilting the bed, 50 means for guiding said thrust bar, a strut composed of a plurality of foldable members interposed between the opposite side of the bed and the under body and adapted when

said members are alined to prevent tilting of the bed in one direction, and devices operated by said power operated means for causing said strut to fold as the bed is tilted in one direction. 55

13. A dump car comprising an under body, a bed mounted thereon and adapted to tilt 60 to discharge its load, a folding thrust bar comprising jointed members, one of said members being pivotally connected with the bed at one side of the axis thereof, power operated means adapted to engage the other 65 member while said members are alined to move the same endwise for tilting the bed, means for guiding said thrust bar, a strut composed of a plurality of foldable members interposed between the opposite side 70 of the bed and the under body and adapted when said members are alined to prevent tilting of the bed in one direction, and devices operated by said power operated means for moving said strut laterally and causing 75 the same to fold as the bed is tilted in one direction.

14. A dump car comprising an under body, a bed mounted thereon and adapted to tilt to discharge its load, a strut composed of a 80 plurality of foldable members, the upper end portion of said strut being pivotally connected with the bed, and the lower end portion thereof being adapted to bear on the under body to prevent tilting of the bed 85 in one direction when said strut is in operative position, means for moving said strut out of operative position, and a spring tending to restore said strut to its operative position. 90

15. A dump car comprising an under body, a bed mounted thereon and adapted to tilt to discharge its load, a strut composed of upper and lower members connected together by a knuckle joint, said strut being 95 pivotally supported at one end to swing laterally between one side of the bed and the under body, the other end of said strut having a thrust bearing on the under body for preventing tilting of the bed in one direction when said members are in operative 100 position, means for moving said strut out of operative position, and a spring tending to restore said strut to its operative position.

JAY B. RHODES.
